UNITED STATES PATENT OFFICE

EDWARD W. BULLARD, OF SAN FRANCISCO, CALIFORNIA

SAFETY HAT

Application filed May 21, 1928. Serial No. 279,251.

The invention relates to a safety hat, and particularly to the type of hat worn by miners and firemen.

An object of the invention is the provision of a safety hat having a supporting bracket for holding a light.

Another object of the invention is the provision of a safety hat having a supporting bracket which is insulated from the hat.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

The figure is a perspective view of a safety hat equipped with the supporting bracket of my invention.

Safety hats of the type used by miners, firemen and others, who must protect themselves from falling objects, charged wires, and other hazards, are generally made of non-conducting materials. However, in many of these occupations it is essential for the wearer of the hat to carry a lamp, either an electric lamp or an oil lamp, which is preferably carried by a bracket riveted to the hat. It is not infrequent that a worker snags a live wire with the supporting bracket, and is shocked or burned by the current which passes thru the metallic fastening means to the wearer. It is therefore the broad object of my invention to provide a safety hat having a light supporting bracket which is mounted on and insulated from the hat.

In detail, my invention comprises a safety hat of non-conducting material, and having a brim or visor 2 suitably secured to a crown portion 3. The hat construction is described in detail in my co-pending applications for

United States Letters Patent, Serial Numbers 166,616 and 203,825, filed February 8, 1927, and July 6, 1927, respectively.

A lamp supporting bracket is provided which has an aperture 7 and a slot 8 in which a lamp may be detachably seated. The brack-

et is preferably formed of thin sheet metal; and comprises a central or upright portion 11, a lower flange 12 extending at an angle of about 45° from one side thereof, and an upper flange 13 extending at an angle of substantially 90° from the other side of the central portion. The sides 14 of the bracket are rolled or bent over to form a channel to reinforce the device and to hold the strip of fibrous material 16 provided to absorb heat from the lamp. This is particularly desirable when a carbide lamp is used, as it generates a considerable amount of heat which would cause the hat to become uncomfortably warm if the fibrous strips were omitted.

The lower end 12 of the bracket is secured to the brim 2 of the hat by the rivets 17; and since the material from which the hat is made is a non-conductor of electricity, and no portion of the head of the wearer touches the rivets on the underside, this method of fastening is perfectly safe. This however, is not the case with the opposite end of the bracket. The head of the user is likely to be in contact with the inside of the crown so that rivets driven directly thru the bracket into the crown could transmit a current dangerous to the wearer. To provide against this a strip 21 of insulating material is secured to the crown 3 by the rivets 22. The strip is preferably bent outwardly over the heads of the rivets so that they lie under the strip and are protected by it against accidental contact with a live wire. The upper flange 13 of the bracket is then secured to the insulating strip by the rivets 23. The space between the rivets 22 and 23 is such that there is no danger of the current arcing across the gap.

Should the wearer of a safety hat equipped with the supporting bracket of my invention snag a live wire with any portion of his hat it would be impossible for the current to shock or burn him.

I claim:

1. A safety hat comprising a visor and crown of non-conducting material, an insulating strip riveted to said crown and bent outwardly over said rivets, a supporting bracket riveted at one end to said visor and at the other end to said insulating strip.

2. A safety hat comprising a visor and crown of non-conducting material, a curved insulating strip, metal rivets for securing one end of said strip to the crown, said rivets terminating exteriorly of the crown on the inside of the curve of the strip and below the free end, and a supporting bracket secured at one end to the visor and at the other end to the free end of said strip.
- 10 3. A safety hat comprising a visor and a crown of non-conducting material, an insulating strip, rivets securing said strip to the crown, said insulating strip comprising a guard overlying said rivets to prevent electrical contact therewith, and a supporting bracket riveted at one end to said visor and at the other to said strip.
- 15 4. A safety hat comprising a visor and crown of non-conducting material, an insulating strip adapted to form a support, and rivets securing the strip to the crown, said strip being turned outwardly over the rivets to provide a guard therefor.
- 20 5. A safety hat comprising a visor and crown of non-conducting material, supporting means for an object adapted to be carried on the hat and secured at one end to the visor, the other end of said supporting means comprising an insulating strip, metallic means securing the insulating strip to the crown, said strip being turned outwardly over the securing means to provide a guard therefor.

In testimony whereof, I have hereunto set
35 my hand.

EDWARD W. BULLARD.
